UNITED STATES PATENT OFFICE.

PAUL S. BARBAY, OF SAN FRANCISCO, CALIFORNIA.

LOCK.

Application filed January 5, 1921. Serial No. 435,162.

To all whom it may concern:

Be it known that I, PAUL S. BARBAY, a citizen of the United States, residing at San Francisco, in the county of San Francisco and State of California, have invented new and useful Improvements in Locks, of which the following is a specification.

This invention relates to a door lock.

It is the principal object of the present invention to provide a combined key and knob operated door lock equipped with means whereby the lock may be rendered ineffective for operation by either the key or the knob when desired, or may be operated by the key alone as controlled by release means on the inside of the door, all of which construction is compact in its arrangement and direct in operation.

The present invention contemplates the use of a lock structure adapted to be mounted against the inner face of a door and to be equipped with a single bolt, which may be actuated by rotation of knobs on the opposite sides of the door after operation of a key mechanism accessible to the front of the door, said structure being further fitted with release means on the inside of the door rendering the knob and key mechanisms inoperative when desired.

The invention is illustrated by way of example in the accompanying drawings, in which:

Figure 1 is a view in elevation showing one form of the lock mechanism, with its case removed to more clearly disclose the parts when in condition for operation by the knob and with parts broken away to more clearly disclose the details of the construction.

Fig. 2 is a view in elevation similar to Fig. 1 showing the parts of the lock in their inoperative positions.

Fig. 3 is an enlarged fragmentary view through the lock bolt mechanism as seen on the line 3—3 of Fig. 16.

Fig. 4 is a view in perspective showing the bolt cam.

Fig. 5 is a view in perspective showing the knob actuated arm.

Fig. 6 is a view in perspective disclosing the key operated trip member.

Fig. 7 is a fragmentary view in elevation illustrating key lever operated bolt.

Fig. 8 is a view in perspective disclosing the knob release pawl.

55

Fig. 9 is a view in perspective of the lock cam.

Fig. 10 is a fragmentary view in elevation showing another form of the invention.

60

Fig. 11 is a view in perspective showing the safety lever of the form of the device shown in Fig. 10.

Fig. 12 is a view in perspective showing the connection of the lock mechanism with the bolt in the form of the device shown in Fig. 10.

65

Fig. 13 is a view in elevation showing the manner of installing the lock ferrule.

Fig. 14 is a fragmentary view in section and elevation showing the lock ferrule construction.

70

Fig. 15 is a fragmentary view in elevation showing the edge of a door and the present invention applied thereto.

Fig. 16 is a fragmentary view in front elevation, showing the lock.

75

Fig. 17 is a view in perspective showing the lock cam employed in the structure disclosed in Fig. 10.

80

Fig. 18 is a view in perspective showing the safety knob.

Referring more particularly to the drawings 20 indicates a case, within which a lock structure is housed. This case is adapted to lie flush along one of the side faces of a door and in position over a back plate 21, which is preferably secured direct to the door. A lock barrel opening 22 is formed through the door at a point in the rear of the case and is in communication with a bolt passage way 23, extending at right angles thereto, and terminating in the edge of the door. At a point higher up in the door a knob opening is provided. Thus it is only necessary to bore two holes through the door and one hole in the edge thereof. A barrel lock 24 is suitably mounted within the opening 23, while a lock bolt 25 is positioned within a bar case 26 disposed within opening 23. A knob shaft 27 extends through the knob opening in the door and receives knobs 28 at the opposite ends thereof.

90

95

100

105

In the form of the invention shown in Figs. 1 to 9, inclusive it is intended that

the operation of the knobs shall actuate the bolt and that this action shall be controlled by the movement of a key within the lock 24 or rotation of a safety knob 29 on the 5 face of the case 20, which is disposed within the room. This is brought about by the assembled mechanism particularly disclosed in Figs. 1 and 2, where it will be seen that a knob actuated arm 30 is secured upon the 10 squared knob shaft 27, and is fitted with a lift finger 31 pivoted upon a pin 32 at its outer end. The upper end of the finger 31 is formed with a squared face 33 adapted to be borne against by a spring finger 34. Due 15 to the angular position of the face 33 relative to the general position of the finger the spring lever will normally act to throw the catch portion of the finger out of engagement with a lug 36 of a draw rod 37. 20 An expanding spring 38 constantly acts on the spring lever 34 to force it downwardly and into continued contact with the face 33 of finger 31. Reciprocal movement of the finger 31 is brought about by oscillation 25 of the knob actuated arm 30, this movement at the same time being accompanied by a slight swinging movement of the finger around its pivot 32 as the finger is drawn along a face 38' of a wedge member 39. 30 The draw bar 37 is pivotally connected at its lower end with a lever arm 40. This arm is formed with a circular boss 41 extending through an opening 42 in the back plate 21, and being further provided with 35 a squared portion resting in a similar formed seat 43 of a bolt lever 44. This lever is disposed within the opening 22 of the door and when swung in a direction away from the opening 23 will engage a stop 45 as 40 shown in Fig. 12 to retract the bolt 25. The stop 45 is formed on an extension plate 26 of the bolt 25 as more clearly shown in Figs. 3 and 12. Adjustment of the bolt is provided by an interposed threaded shaft 45 47, to which the plate 46 is secured, and which in turn is threaded into the end of the bolt. Lock nuts 49 are provided to set the members in their adjusted positions. The bolt case 26 is suitably formed to receive 50 an expansion spring 50, which will act to force the bolt in its outermost position at all times. Due to this arrangement rotation of the door knob with the resultant lifting movement of the lever 30 will normally 55 act to cause the catch 35 of finger 31 to engage the lug 36 of draw bar 37 and swing the lever 40 upwardly, at the same time swinging bolt lever 44 rearwardly and retracting the bolt 25. A spring 51 is used 60 to normally swing the draw bar in a position to be engaged by the fingers 31.

The bolt actuating means as controlled by the knob, may be rendered inoperative by both the key lock 24 or the movement of 65 the safety knob 29. The former mechanism

comprises a trip member 52, which is in the shape of a short arm disposed in a plane parallel to the arm 40 connected with the draw bar 37. This trip member is fitted with a stem 53 extending down through 70 the bolt cam 44. The end of this stem is formed with a squared projection 54, which extends into a slot 55 made in the rotatable part 56 of the barrel lock mechanism. The trip member is provided with an inwardly 75 projecting lug 57, which is of substantially the thickness of the arm 40, which it overhangs. The end of this lug is relieved for a purpose which will hereinafter be described. Rotation of the trip member 52 80 is independent of rotation of the arm 40 and is intended to actuate a lock cam 58. This cam is mounted for free rotation upon a pin 59, to which the safety knob 29 is rigidly secured. This lock cam is provided 85 with an extending lug 60, which may be encountered by the trip member 52 as it swings in the direction of the arrow —a—, as indicated in Fig. 2. The opposite side of the trip member is formed with a series of gear 90 teeth 61 in mesh with the gear segment 62. This segment forms a part of a release finger 63, which may swing in the direction of the arrow —b— and force the draw bar 37 to an inoperative position. A V-shaped 95 catch recess 64 is formed in the edge of the trip member 52, and may be engaged by the hook end of a catch arm 65, which may swing upon its pivot 66 as influenced by a spring 67. Return movement of the 100 member 63 is limited by a stop pin 68, while the extreme outward movement of the draw bar 37 is limited by a stop pin 69.

The safety knob 29 renders the knob mechanism inoperative by means of a release pawl 70 secured thereto and adapted to rotate therewith. This pawl has an extension 71 at one side of its axis, which is intended to swing out against a leaf spring secured to the side face of the draw bar and to thereafter force this spring flat and continue to swing until the draw bar has been moved in the direction of the arrow —c— to the position indicated in Fig. 2. The opposite side of the release pawl is formed 115 with an arcuate face 72, engaging the point of the catch 65 and swinging it out of its locked position relative to the recess 64. An extending arcuate portion 73 adjoins the other face and in the extreme locking 120 position of the pawl rests directly against the catch portion of the member 65, tending to more rigidly secure the pawl in its locked position.

Reference being had to Fig. 10, a modification of the invention is shown in which the release pawl 70 is eliminated and a safety lever 74 is used in its place. This lever is rigidly secured to the end of the pin 59 and may be swung around to engage the 130

extension 60 of the lock cam 58 or to strike the catch member 65 and swing it to a release position. All of the remaining mechanism is identical with that previously described.

In order to make the invention simple in its application, the barrel lock 24 may be readily secured in position in the manner shown in Figs. 13 and 14. This is done by 10 providing extension fingers 75 at the end of the barrel, which fingers have serrated outer faces 76 at their ends. A wedge washer 77 is driven into the opening 22 and between the fingers 76, forcing them outwardly into the wood of the door, and rigidly securing the lock barrel in position.

In operation the lock is normally in a position so that the bolt 25 may be reciprocated by rotation of either knob. This normal position is clearly indicated in Fig. 1, where it will be seen that upward swinging movement 30 in the direction of the arrow —d— will lift the finger 31, causing its catch to engage the lug 36 of bar 37 and draw this bar upwardly in the direction of the arrow —e—. Upward movement of the arm 40 will then be produced, which movement will be imparted to the bolt cam 44, and this cam in turn will retract the bolt. If the door is to 20 be locked by a key a rotation of the key will cause the member 56 of the lock barrel to be rotated. This will turn the stem 53 of the trip member 52 and will swing this member in the direction of the arrow —a—, causing 30 the lock cam 58 to rotate in an opposite direction around the pin 59. The engagement of the cam with member 63 will cause this member to swing outwardly, thus disposing the projection 60 of the lock cam and the 35 member 63 against the side of the draw bar, to forcibly hold the draw bar in an inoperative position as wedged between these two members and the pin 69. The draw bar will be held in this position due to the engagement 40 of the catch 65 with the recess 64 of the lock cam. This action may be discontinued, however, by movement of the safety knob and rotation of the release pawl 70. Rotation of this pawl in the direction of the 45 arrow —f— will cause the end 71 to strike the bar and hold the same in its locked position, but at the same time will swing the catch 65 out of engagement so that a return of the pawl will release the draw bar and 50 permit it to move to its position for engagement with the finger 31. As previously stated the action of the mechanism 10 will be substantially the same as this with the exception that the member 74 will take the place of 55 the member 70 to cause indirect locking of the draw bar by the members 60 and 63.

It will thus be seen that the lock here disclosed is quite compact in its design and arrangement, may be easily installed and readily operated to become locked from either

side of the door and to be rendered entirely inoperative by manipulation from the inside of the door.

While I have shown the preferred form of my invention, as now known to me, it will be understood that various changes might be made in the combination, construction, and arrangement of parts, without departing from the spirit of the invention, as claimed.

Having thus described my invention, what I claim and desire to secure by Letters Patent is:

1. A lock comprising a rotatable knob shaft having knobs disposed at its ends, a lock bolt adapted to normally project from the edge of the door, connecting means between the bolt and the knob shaft, whereby rotation of the knob shaft will retract the bolt, key controlled means on one side of the door for rendering said connecting means ineffective, and a single means on the opposite side of the door for optionally rendering the key control means and the connecting means ineffective.

2. A lock comprising a reciprocal bolt, a rotatable knob shaft connected to the bolt and normally adapted to retract the same, key control means for removing the connection between the bolt and the knob shaft and means whereby a single operation may render the key controlled means and the connection between the knob shaft and the bolt ineffective.

3. A lock comprising a knob shaft, a bolt normally projecting from the edge of the door and retractable by rotation of the knob shaft key controlled means on the outside of the door for rendering the knob shaft ineffective, and a turnable member on the inside of the door for rendering both the key controlled means and the knob shaft ineffective.

4. A lock comprising a knob shaft extending through the door and having a knob at each end, a lock bolt projecting from the edge of the door and normally retractable by the knob shaft, a key controlled mechanism on the outside of the door for preventing the knob shaft from retracting the bolt, and a turnable member incorporated in the construction of the lock for preventing both the key controlled mechanism and the knob shaft from retracting the bolt.

5. In combination with a retractable door bolt normally adapted to be controlled by a knob shaft and a key controlled mechanism, of a member adapted to be controlled from one side of the door and adapted when actuated to prevent the knob shaft and the key controlled mechanism from retracting the bolt.

6. In combination with a door bolt and a knob shaft and key controlled mechanism which are normally operatively connected

to the door bolt, of means controlled by a member on one side of the door for discontinuing the operative connection between both the knob shaft and key controlled mechanism and the door bolt.

7. A lock comprising a lock case adapted to be secured against the inner face of a door, a knob shaft extending through said case and the door and carrying knobs on its opposite ends, a reciprocating bolt projecting from the edge of the door and in a horizontal plane below that of the knob shaft, rotating means projecting from the lock case for producing reciprocation of the bolt, a catch member adapted to be raised and lowered by rotation of the knob, and a draw bar normally connecting the catch member of the knob shaft with the rotating means of the bolt.

8. A lock comprising a lock case adapted to be secured against the inner face of a door, a knob shaft extending through said case and the door and carrying knobs on its opposite ends, a reciprocating bolt projecting from the edge of the door and in a horizontal plane below that of the knob shaft, rotating means projecting from the lock case for producing reciprocation of the bolt, a catch member adapted to be raised and lowered by rotation of the knob, a draw bar normally connecting the catch member of the knob shaft with the rotating means of the bolt, and key operated means accessible from the outside of the door for disconnecting the draw bar from the catch member, and holding the same in its disconnected position.

9. A lock comprising a lock case adapted to be secured against the inner face of a door, a knob shaft extending through said case and the door and carrying knobs on its opposite ends, a reciprocating bolt projecting from the edge of the door and in a horizontal plane below that of the knob shaft, rotating means projecting from the lock case for producing reciprocation of the bolt, a catch member adapted to be raised and lowered by rotation of the knob, a draw bar normally connecting the catch member of the knob shaft with the rotating means of the bolt, and safety means upon the inside of the door for disconnecting the draw bar from the catch member.

10. A lock comprising a lock case adapted to be secured against the inner face of a door, a knob shaft extending through said case and the door and carrying knobs on its opposite ends, a reciprocating bolt projecting from the edge of the door and in a horizontal plane below that of the knob shaft, rotating means projecting from the lock case for producing reciprocation of the bolt, a catch member adapted to be raised and lowered by rotation of the knob, a draw bar normally connecting the catch member of the knob shaft with the rotating means of the bolt, safety means upon the inside of the door for disconnecting the draw bar from the catch member, and key operated means accessible from the outside of the door for disconnecting said draw bar from the catch member, and holding the same in its disconnected position.

PAUL S. BARBAY.
